Primary Examiner — John A Voytek

(74) Attorney, Agent, or Firm — Thompson Hine LLP

(57) **CLAIM**

The ornamental design for tire tread as shown and described.

DESCRIPTION

FIG. 1 is a perspective view of the design;

FIG. 2 is a front view of the design of FIG. 1;

FIG. 3 is a side view of a first side of the design of FIG. 1;
FIG. 4 is a side view of a second side of the design of FIG. 1; and,

FIG. 5 is a detail view of a portion of FIG. 2.

In the drawings, the broken lines depict environmental
subject matter only and form no part of the claimed design.**1 Claim, 5 Drawing Sheets**(56)

UNITED STATES PATENT AND TRADEMARK OFFICE
CERTIFICATE OF CORRECTION

PATENT NO. : D1,091,440 S
APPLICATION NO. : 29/919395
DATED : September 2, 2025
INVENTOR(S) : Henri Sakari Kossi and Mikko Valtteri Sironen

Page 1 of 1

It is certified that error appears in the above-identified patent and that said Letters Patent is hereby corrected as shown below:

On the Title Page

The broken line description portion of the DESCRIPTION reads:

“In the drawings, the broken lines depict environmental subject matter only and form no part of the claimed design.”

It should read:

--In the drawings, the relatively long-dash broken lines depict environmental subject matter only and form no part of the claimed design. The relatively short-dash broken lines in Fig. 2, showing the source of the detail view of the tire tread shown in Fig. 5, form no part of the claimed design.--

Signed and Sealed this
